UNITED STATES PATENT OFFICE.

RICHARD HOELEMANN, OF BROOKLYN, NEW YORK.

CLOSURE DEVICE FOR BOTTLES AND OTHER VESSELS.

No. 819,139.

Specification of Letters Patent.

Patented May 1, 1906.

Application filed September 1, 1905. Serial No. 276,695.

To all whom it may concern:

Be it known that I, RICHARD HOELEMANN, a citizen of the United States, residing at Brooklyn, in the county of Kings and State 5 of New York, have invented certain new and useful Improvements in Closure Devices for Bottles and other Vessels, of which the following is a specification such as will enable those skilled in the art to which it appertains to make and use the same.

This invention relates to closure devices for bottles, jugs, jars, and similar vessels; and the object thereof is to provide an improved device of this class by means of which 15 a bottle or similar vessel may be quickly and easily sealed or closed in such manner as to prevent the ingress of air therethrough or the escape therefrom of gases or liquids under pressure.

20 In the drawings forming part of this specification I have shown my invention applied for the purpose of closing a bottle, and the invention is fully disclosed in the following specification, of which the accompanying 25 drawings form a part, in which the separate parts of my improvement are designated by suitable reference characters in each of the views, and in which—

Figure 1 is a side view of a part of the neck 30 of a bottle and showing a part of my improvement; Fig. 2, a similar view, but showing the neck of the bottle in a slightly-different position; Fig. 3, a central vertical section showing the cap or closure device proper applied to the neck; Fig. 4, a plan view of the neck with the cap or closure device proper removed; and Fig. 5, a section of the cap or closure device proper at right angles to that shown in Fig. 3.

40 In the drawings forming part of this specification I have shown at *a* the neck portion of a bottle, and said neck is enlarged at the top thereof, as shown at *a*², and in the opposite sides thereof are formed circular grooves *a*³, which extend half-way around the neck and are closed at one end by a vertically-arranged lug, projection, or partition *a*⁴, and the opposite ends thereof communicate with vertically-arranged recesses *a*⁵ in the opposite 45 sides of the enlarged portion *a*² of the neck of the bottle. The vertically-arranged recesses *a*⁵ are of considerable width, and the top walls *a*⁶ of the grooves *a*³ from about midway of the length of said grooves are curved upwardly, as shown at *a*⁷, and the top side walls 50 of the recesses *a*⁵ are preferably rounded or

beveled, as shown at *a*⁸. I also provide a cap or cover *b*, which constitutes the closure device proper and which is made of sheet metal and provided with a depending flange or rim *b*², at the opposite sides of the bottom edge of which are inwardly-directed spring lugs or projections *b*³, formed from depending strips of the material of the flange or rim *b*², rolled up, as shown in Figs. 3 and 4. Within the 60 cap or cover *b* is placed and secured a packing-disk *c*, of cork or any other suitable material, and in order to close the bottle the cap or cover *b* is pressed downwardly thereon, in which operation the spring lugs or projections *b*³ pass downwardly through the recesses *a*⁵. The cap or cover *b* is then turned to the right, and the spring lugs or projections *b*³ coming in contact with the upwardly-inclined walls *a*⁷ on the top portion of the 65 neck and above the grooves *a*³ draw said cap or cover firmly down upon the neck of the bottle, and this operation securely closes the bottle, as will be readily understood.

It will be seen that the portion of the top 80 and bottom walls of the grooves *a*³ adjacent to the stops *a*⁴ are parallel, and when the spring lugs or projections *b*³ are forced thereinto the cap or cover *b* is securely held and cannot be removed without being turned in 85 the opposite direction, and this operation requires considerable force. It will be understood that the spring lugs or projections *b*³ form an important feature of this invention for the reason that they exert at all times a 90 spring action which operates and holds the cap or cover *b* in place.

My improvement is particularly adapted for use in closing beer-bottles and other bottles containing liquid and gases under pressure; but the same may also be employed in closing fruit jars or cans, and it will be apparent that the same may be used in connection with jugs and other vessels used for a similar purpose.

Having fully described my invention, what I claim as new, and desire to secure by Letters Patent, is—

1. A bottle or similar device provided with a neck, the top portion of which is enlarged 105 and provided in its opposite sides with vertically-arranged recesses which communicate with annularly-arranged grooves formed in the enlarged portion of the neck and provided with stops, the top walls of said grooves 110 adjacent to said recesses being inclined upwardly, and a closure device provided with

2
a depending flange or rim which extends downwardly to said annularly-arranged grooves and the bottom edge of which is provided with inwardly-directed spring lugs or projections adapted to enter said recesses and grooves, substantially as shown and described.

2. A bottle or similar device provided with a neck, the top portion of which is enlarged and provided in its opposite sides with vertically-arranged recesses which communicate with annularly-arranged grooves formed in the enlarged portion of the neck and provided with stops, the top walls of said grooves adjacent to said recesses being inclined upwardly, 15 and a closure device provided with a depending flange or rim which extends downwardly to said annularly-arranged grooves and the bottom edge of which is provided with inwardly-directed spring lugs or projections 20 adapted to enter said recesses and grooves, said lugs or projections being in the form of spring-rolls, substantially as shown and described.

3. A bottle or similar device provided with a neck, the top portion of which is provided 25 in its opposite sides with vertically-arranged recesses which communicate with annularly-arranged grooves formed in the top portion of the neck and provided with stops, the top walls of said grooves adjacent to said recesses being inclined upwardly, and a closure device provided with a depending flange or rim which extends downwardly to said annularly-arranged grooves and the bottom edge of which is provided with inwardly-directed 30 spring lugs or projections adapted to enter said recesses and grooves, substantially as shown and described.

In testimony that I claim the foregoing as my invention I have signed my name, in presence of the subscribing witnesses, this 31st day of August, 1905.

RICHARD HOELEMANN.
